HYPHOCHLORITE BLEACHING COMPOSITIONS
 Alfred F. Steinhauer and Joseph C. Valenta, Midland,
 Mich., assignors to The Dow Chemical Company,
 Midland, Mich., a corporation of Delaware
 No Drawing. Filed May 25, 1961, Ser. No. 112,512
 2 Claims. (Cl. 252—187)

The present invention relates to novel and useful improved bleaching solutions. More particularly the present invention concerns the use of a novel surfactant in hypochlorite bleaching solutions to impart foaming and additional cleaning and bleaching power to such solutions.

It has now been found that an alkali metal salt of an alkylated diphenyl oxide sulfonic acid, when added in amounts of from about 1 to 100% by weight based on the active bleaching agent of a bleaching composition, will enhance bleaching, cleaning and brightening power of compositions of both household and industrial strengths. The desirability of adding a surfactant is increased since the foaming attendant with the use is an indication of the amount of bleaching solution added.

The alkylated diphenyl oxide sulfonic acid alkali metal salts and their nuclearly mono and dichlorinated derivatives, suitable for use in accordance with the present invention are those having from 8 to 22 carbon atoms in the alkyl chain and an average of from 1.8 to 2.3 sulfonate moieties per diphenyl oxide moiety.

The following examples illustrate the present invention but are not to be construed as limiting:

EXAMPLE 1

The solubility of 0.1% by weight of surfactant in 5% aqueous sodium hypochlorite solutions at 25° C. for various surfactants is recorded in Table I.

2

Table I

		Solubility
Alkylbenzene sodium sulfonate ¹	-----	I
Lauryl alcohol sulfate (technical grade) ²	-----	I
Sodium lauryl sulfate ³	-----	I
An alkylolamide ⁴	-----	I
Isooctylphenyl polyethoxyethanol ⁵	-----	7 SC

³ Duponol C, manufactured by E. I. du Pont de Nemours and Co.		
⁴ Stepan LDA, manufactured by Stepan Chemical Co.		
⁵ Triton X100, manufactured by Rohm & Haas Co.		
⁶ Tergitol 08, manufactured by Union Carbide Co.		

⁷ Became cloudy with precipitate after 6 weeks' shelf storage.

⁸ Clear after 4 months' shelf storage.

EXAMPLE 2

The surface tension of various concentrations of alkylated diphenyl oxide disulfonic acid, sodium salt, in aqueous 5% sodium hypochlorite solutions is reported in Table II below. The test solution was prepared from 27 ml. of aqueous 5% hypochlorite solution containing 0.2% or 0.4% by weight of a surfactant and 973 ml. of tap water having 70 p.p.m. hardness at 25° C.

Table II

30	Surfactant	Concentration of Surfactant in Test Solution (Percent by Weight)	Surface Tension dynes
Sodium dodecyldiphenyl oxide disulfonate	0.0054	43.0	
Do	0.0108	41.1	
Sodium pentadecyldiphenyl oxide disulfonate	0.0054	46.5	
Do	0.0108	45.5	
No Surfactant	-----	55.2

² Tergitol 08.

³ Triton X100.

⁴ Sample was cloudy with precipitate. Sample was shaken to disperse precipitate before test.

3
EXAMPLE 3

Two grams of one of several surfactants, e.g., sodium pentadecylidiphenyl oxide sulfonate, was added to 1000 grams of aqueous 5% hypochlorite solution ("Clorox"). Twenty-seven ml. of the above solution was added to 973 ml. water having a hardness of 70 p.p.m. as CaCO_3 . The above solution was then tested on the Ross-Miles Foam Tower. The test is carried out in the following manner.

One hundred cubic centimeters of a solution prepared in the above manner was pipetted into the Foam Tower directing the flow in such a way that it flows down the side walls of the tower so as not to produce any foam. The same solution was placed in a dropping funnel, the stopcock opened, and the 200 cc. of solution allowed to fall into the 100 cc. of solution in the bottom of the tower. The height of the foam, in millimeters, was measured immediately and each minute of standing for a total of five minutes and the measurements recorded in Table III.

A second series of tests was carried out to determine the stability of the class of compounds of the present invention after standing for 6 weeks. The Ross-Miles Foam Tower test was carried out in the above manner and the results recorded in table III.

EXAMPLE 4

The following example illustrates the effectiveness of the surfactants in water of various hardnesses. The Ross Miles Foam Tower test was conducted in the manner of Example 2 using a solution prepared from 27 ml. of an aqueous 5% hypochlorite solution containing 0.2% by weight of sodium pentadecylidiphenyl oxide disulfonate and 973 ml. of water of various hardnesses. The results of such tests are indicated in Table IV.

							90

15 It is to be understood that bleaching agents other than sodium hypochlorite can be enhanced in the foregoing manner. Some of such agents are the hypochlorites, i.e., sodium, potassium, calcium or magnesium hypochlorite, as well as chloride of lime ($\text{CaCl}\cdot\text{Ca}(\text{ClO})$).

20 We claim:

1. An aqueous 5 percent by weight sodium hypochlorite bleaching solution containing from about 1 to 100% by weight based on the active bleaching agent of a compound selected from the group consisting of alkali metal salts of an alkylated diphenyl oxide sulfonic acid and their nuclearly mono and dichlorinated derivatives having from 8 to 22 carbon atoms in the alkyl moiety and an average of from 1.8 to 2.3 sulfonate moieties per diphenyl oxide moiety.
2. An aqueous 5 percent by weight sodium hypochlorite bleaching solution containing from 1 to 100% by weight based on the active bleaching agent of a sodium dodecyl diphenyl oxide sulfonate having an average of about 2 sulfonate radicals per diphenyl oxide moiety.
